UNITED STATES PATENT OFFICE.

JOHN C. BOGLE, OF OAK PARK, ILLINOIS, ASSIGNOR TO COOK ELECTRIC COMPANY, OF CHICAGO, ILLINOIS, A CORPORATION OF ILLINOIS.

ELECTRIC FUSE.

Application filed December 4, 1922. Serial No. 304,654.

My invention relates to electric fuses and it has special reference to fuses that are known as enclosed renewable fuses.

More particularly my invention relates to an improved electric fuse, in which a chamber containing the fusible element communicates with the outer air through a restricted passageway comprised in a washer or stopping member of such form that the gases generated by the vaporization of the fusible element are properly vented from this chamber, but the flame thus occasioned is precluded from extending exteriorly of the fuse by reason of said venting passageway. To meet properly the fire underwriters' specifications, an enclosed renewable fuse should wholly confine the flame from the fusible element to the interior of the fuse.

An object of my invention is to provide a fireproof enclosed renewable fuse, which comprises elements that may be recurrently used with the exception of the fusible element.

Another object of my invention is to provide a fuse of the character indicated above, in which the passageways serving to vent the fuse for expelling the gases from the interior thereof may be maintained permanently open and substantially free from clogging deposits which tend to form from the vapors generated at the time of the exploding of the fusible element.

A further object of my invention is to provide a fusible element for a fuse of the character indicated above, which is so designed as to avoid the production of unnecessary heat and to permit the heat that is produced to be quickly radiated to the exterior of the fuse.

A further object of my invention is to provide a device of the type indicated above, which is of a simple, durable construction and inexpensive of manufacture.

Further objects of my invention will appear upon reference to the following specification and accompanying drawings, in which—

Figure 1 is a view, partially in elevation and partially in section, of an enclosed renewable fuse constructed in accordance with my invention;

Fig. 2 is a disassembled view showing in detail, portions of the several elements comprising the fuse of Fig. 1;

Fig. 3 is a sectional view taken on line 3—3 of Fig. 1;

Fig. 4 is a modified form of a fuse having a removable washer of the general character illustrated in Fig. 1, but in which the cap is not provided with a knife blade form of terminal;

Fig. 5 is a sectional view taken on line 5—5 of Fig. 4;

Figs. 6 through 9^a are sectional views of modified forms of washer members;

Figs. 10, 11, 12, 13 and 14 are views similar to those of Figs. 1, 2, 3, 4, and 5 respectively, but showing a modified form of my invention in which a notch is formed in a ferrule member at the end of the fuse shell, providing a passage for the fuse link to the exterior of the fuse shell;

Fig. 15 is a detail perspective view of the fuse link used in connection with my invention.

Referring to the structure shown in Figs. 1, 2 and 3, a fuse link 1 is contained within an insulating shell 2 that serves as a container for the fuse. The shell 2 is provided with threaded ferrules 3 and 4 at its ends, which are engaged by venting washers 5, terminal members 6 and cap members 7.

The two ends of the fuse may be of similar construction, and consequently only the upper end, as shown in Fig. 1, will be described in detail.

The fuse link 1 may comprise a fusible element 8 formed preferably in the shape of a ribbon and of a metal having the proper fusing characteristics, such as zinc. The fusible element 8 is rigidly supported centrally of the shell 2 and out of contact with the walls thereof by elongated supporting and connecting terminals 9 and 10. The fusible element 8 may be fixed to the terminals 9 and 10 by bending over side edges 11 of the terminals for a short distance at their inner ends, thus forming clamping means as shown in Fig. 15. Or if desired, the fusible element may be soldered to the terminals as indicated in Fig. 11 at 9^a and 10^a. As appears in Fig. 15, the terminals 9 and 10 may be formed with stiffening ribs 12 and 13 along their edges. It is advantageous in a fuse of this type to support the fusible element with sufficient rigidity to prevent all possible contact of the element with the containing shell, even when the element expands

2
or becomes distorted as a result of excessive heating caused by heavy currents flowing therethrough. If the fusible element is permitted to come into contact with the containing shell, a certain amount of heat as a consequence will be transmitted away from the fusible element. The amount of this heat cannot be predetermined or controlled and hence destroys the advantages of carefully designing the fusible element. In view of the above, the fusible element as shown is of a short length in comparison with the total length of the fuse link and this short length of fusible material is furthermore rigidly supported by the terminals 9 and 10 in the desirable central location.

10 The terminals 9 and 10 are preferably constructed of a metal having relatively high electrical and heating conductivity, such as 20 copper. This type of construction has several important advantages, which will now be outlined.

25 One of the problems of fuse design is to provide means for carrying away the heat generated by the link when currents of a lower value than what are intended to cause the fuse to operate are traversing the fuse. That is to say, when normal currents are applied to the fuse the thermal path must be 30 adequate to carry away the heat at the rate it is being applied, once a condition of stability has been reached.

35 The continuous zinc link meets with difficulties in that there is a thermal gradient from the hottest point or points to the outer ends, which carry away the heat of the fuse proper to the external parts exposed to the air.

40 The addition of copper terminals of sufficient size extending part way into the shell of the fuse from both ends, limits the effective heating length of the zinc strip which is connected between these copper terminals. The cross-section of the copper terminals is 45 such that the normal current is not sufficient to produce any great amount of heat in the copper itself. Therefore, by far the greatest amount of heat generated by the fuse link comes from the short zinc strip lying between its copper terminals, and the copper terminals having no great amount of heat produced therein are much better enabled to carry off the heat produced in the zinc. A two-fold purpose is thus accomplished, first, 55 of limiting the total quantity of heat generated by the normal current, and, second, the provision of a better thermal path to the outside than can be obtained from a link made entirely of zinc.

60 The foregoing description has related solely to the advantages of this link under normal current conditions. I shall now outline the advantages of this link under short-circuit conditions.

65 On short-circuit conditions my experi-

ence has shown that the zinc first melts at its hottest point or points, then volatilizes in a resulting arc. The arc or arcs thus established tend to continue as long as they are fed by metallic vapor from the volatilized link. The duration of this process of volatilization determines in fuse design the violence of the short-circuit conditions within the fuse. Naturally anything tending to limit the length of time and the amount of metal so consumed tends also to reduce the destructive force produced within the fuse barrel.

70 I have found on repeated tests that the arc fed by the burning zinc strip continues until the ends of the copper link terminals are reached. At this point the copper link terminals exert a cooling action on the arc and the latter is promptly extinguished with 75 no appreciable burning of the copper link terminals.

80 In a solid zinc link under short-circuit conditions, I find that the whole link is destroyed, even that portion of the link extending to the external terminals of the 85 fuse. This needless destruction of metal results in the throwing out of melted metal in every direction within the fuse barrel, and this, I find adheres to the threads of the 90 external connections making it difficult or impossible to remove the latter. It also tends to clog any venting passages which 95 may be provided in the ends of the fuse structure.

100 The terminals 9 and 10 are extended in a curved form, as shown at 14 and 15 in order to conform to the contour of washer 5. The ends of terminals 9 and 10 are then bent down into contact with the faces of washers 5.

105 The washer 5 comprises a cup-shaped shell member 16, having a body portion of substantially cylindrical shape and having a rounded or dome-shaped inner end 17. It has been found that a shell member of this 110 shape can be very quickly and easily inserted within the ferrules 3 and 4. The shell member 16 is provided on its interior with means comprising baffle plates 18 for forming a tortuous venting passage through the 115 shell member. An opening 19 is provided substantially at the center of the dome-shaped portion 17 and permits the gases produced in the shell 2 to escape into the 120 washer shell 16. The opening 19 is located in the position shown in order that the particles of melted metal thrown from the fusible element 8 when melting will be deflected 125 away from this opening by the dome-shaped portion 17, thereby avoiding the possibility 130 of clogging this passage. The baffle plates 18 may be positioned in spaced parallel relation by wire rings 20, such as shown in Fig. 1. Openings 21 are provided in the baffle plates 18 in order to provide passages there-

through. It will be noted that the openings on adjacent baffle plates are located in offset relation with respect to each other in order that a tortuous passage will be formed. The outer end of shell member 16 is closed by a disc 22 having a forced fit at 23 with the walls at the end of shell 16. The disc 22 is further provided with an annular flange 24 for engagement with the outer edge of the ferrule 3. The disc 22 is provided with a centrally located opening 25 for permitting the gases to pass out of shell 16.

In the structure shown in Figs. 1, 2 and 3, a portion of the flange 24 is cut away at 26 in order to provide space for the link terminal 9.

The ferrules 3 and 4 may be formed with threads 27 for engagement with the insulated shell 2. The outer ends of the ferrules 3 and 4 are provided with inturned flanges 28 for engaging the terminal 6 and flange 24.

The terminal 6 may be provided with a knife blade 29 which may be fastened by rivets 30 to a strengthening plate 31 and a base member 32 which engages the flange 28 on ferrule 3. The flange 28 may be provided with a pin 33 extending outwardly through a slot 34 in the base member 32. This pin and slot serve to retain the knife blades 28 at each end of the fuse in their proper relative angular positions. An alternative construction is shown in Fig. 11 where the flange and the base member are provided respectively with coacting detents 33^a and 34^a for a purpose similar to the above described pin and slot construction.

The terminals 9 and 10 are provided at their outer ends with openings 35 and 36 respectively, opposite the openings 25 in the shell members or washers 16. The plate 31, base member 32 and knife blade 28 are also provided with coaxial openings 37, 38 and 39 respectively, forming a passage for the gases from the shell 16.

The terminal member 6 is retained in position at the outer end of ferrule 3 by means of the end cap 7, which is provided with threads 40 for engagement with the ferrules.

The modification shown in Figs. 4 and 5 is similar in construction to the type above described, but is formed with a special type of end cap 41, since in this structure the knife blade terminals 6 are omitted. The end cap 41 is formed to cover completely the end of the fuse with the exception of opening 41^a which is for a purpose corresponding to that of opening 39 in Fig. 1. In other respects, the construction as shown in Figs. 4 and 5 does not materially differ from that above described.

In the type of washer member shown in Fig. 6, baffle plates 42 are used which are provided with the integrally formed annular

spacing flanges 43. In this form, the body or shell member is provided with an integrally formed flange 44 for a purpose similar to the flange 24 in the type above described.

The modification of Fig. 7 differs from that of Fig. 6 only in that a method is shown of spacing the baffle plates by means of embossed lugs 45 formed on one of the plates.

In the modification of Figs. 8 and 8^a, the baffle plates are replaced by a substantially square member 46 having a large mass capable of absorbing the greater portion of the heat of the gases passing through the washer. In this type the gases are allowed to pass through the openings 47 between the cylindrical walls of the shell and the sides of the square member 46.

In the structure of Figs. 9 and 9^a certain of the baffle plates may be provided with openings 21^a which are formed simply by cutting off a segment of the plate at its edge. Openings formed in this manner facilitate the manufacture of the baffle plates. In this structure the shell member is shown with a disc shaped cover 22^a which is welded at 22^b to the shell member.

The structures shown in Figs. 10 through 14 inclusive differ from those shown in Figs. 1 through 5 only in the details above pointed out and in the alternative manner shown in which the terminals 9 and 10 on the fuse link are passed to the exterior of the container. In the modification shown in Figs. 10 through 14, a special type of ferrule 48 may be used, a portion at 49 of which is cut away, for a purpose similar to the opening cut at 26 in the washer 5 above described. As a consequence, the washer member 50 need not be provided with a flange having a portion cut away.

While I have shown and described several embodiments of my invention, it is to be understood that many modifications may be made therein without departing from the spirit and scope of the appended claims, and I desire that only such limitations should be imposed upon my invention as are specifically pointed out in the claims and such as are required by the prior art.

Having thus described my invention, what I claim as new and desire to secure by Letters Patent in the United States, is:

1. A washer for a renewable electric fuse, comprising a shell member, a plurality of spaced substantially parallel baffle plates fitted into the interior of said shell member, and an opening through each of said baffle plates, the openings through adjacent plates being positioned in offset relation with respect to each other to provide a tortuous passage through said shell member.

2. A washer for an enclosed fuse comprising a shell member, a plurality of baffle

plates in the interior of said shell member, and means for positioning said plates in substantially parallel relation comprising annular spacing members.

5. 3. A washer for an enclosed fuse comprising a shell member, a plurality of baffle plates in the interior of said shell member, and means comprising wire rings between said plates for spacing said plates in substantially parallel relation.

10 4. Means for stopping the end of a cartridge type fuse, comprising a substantially cylindrical shell member provided with a rounded end for insertion into the end of 15 said fuse, an opening substantially at the

center of said rounded end, and means in said shell member providing a tortuous passage therethrough.

5. Means for stopping the end of a cartridge type fuse, comprising a cup-shaped 20 shell member for insertion into the end of said fuse, and means for closing the outer end of said shell member comprising a disc having a forced fit with the walls of said shell member, said disc being provided with 25 a flange for engagement with the end of said fuse.

In witness whereof, I have hereunto subscribed my name.

JOHN C. BOGLE.
